EAR CLIP FINDING

Frederick W. Moulson, Rehoboth, Mass., assignor
to B. A. Ballou & Co. Incorporated, a corpora-
tion of Rhode Island

Application May 14, 1949, Serial No. 2,667

Term of patent 14 years

(Cl. D45—1)

To all whom it may concern:

Be it known that I, Frederick W. Moulson, a citizen of the United States of America, residing at Rehoboth, county of Bristol, State of Massachusetts, have invented a new, original, and ornamental Design for an Ear Clip Finding, of which the following is a specification, reference being had to the accompanying drawing, forming a part thereof:

Fig. 1 is a top plan view of an ear clip finding, showing my new design;

Fig. 2 is a side elevation thereof; and

Fig. 3 is an end view thereof.

I claim:

The ornamental design for an ear clip finding, substantially as shown.

FREDERICK W. MOULSON.
